COMPENSATIVE BRIDGE SCORE COMPUTER
Clement E. Birkmeyer, Sr., 609 Prospect St.,
Amarillo, Tex.
Filed Jan. 15, 1965, Ser. No. 425,865
9 Claims. (Cl. 235—78)

This invention relates in general to computers and more particularly to a mechanical compensative computer as applied, in a specific example, to a contract bridge scorer.

Contract bridge, like other games of the whist family, is played in rubbers, a rubber being completed when one side has won two out of three games. Each pair of partners declares, or contracts for, the number of tricks which the pair hopes to win. A game is made when a certain specified number of points are scored. The points scored towards a game are in accordance with the number of tricks contracted for and actually won in fulfillment of the contract, but the value of the tricks in any hand played is dependent upon the suit which has been declared as trump. Thus it may happen that several hands, at each of which a score is made, may be required to be played by a pair of partners before a game is completed. Furthermore, the premiums which are awarded and the penalties which are inflicted vary in amount in accordance with whether a side has, or has not, already won a game in the course of a rubber which is in progress. A side which has won a game is said to be "vulnerable," and may be subjected to severe penalties in case of its failure to take the number of tricks contracted for.

As, in the game of contract bridge, the number of tricks scored towards the winning of a game are only those which the partners, constituting a side, have contracted to take, and because of the penalties which may accrue by reason of failure to take the number of tricks contracted for, it becomes important that the players should at all times have in mind the exact state of the score towards the game in progress, and also the condition as to whether or not their side is vulnerable. To meet this condition it frequently becomes necessary for one player before deciding on a declaration to inquire of another how the score stands, or to lean over the table and inspect the score sheet. Either is annoying, and is objectionable because such an inquiry or inspection may give rise to inferences by the player's partner concerning whether or not the player would have made or not made the declaration had the score been otherwise.

It is the principal object of my invention to provide the correct and complete score results of any hand bid and played at contract bridge, simply by setting the computer to show the amount bid, the suit named as trump, whether vulnerable or not vulnerable, whether not doubled or doubled or re-doubled and the number of tricks taken by bidder.

Another object of this invention is the provision of a compensative computer having multiple inputs and outputs.

Another object of this invention is the provision of visible information to all players as to the status of the bid and the amount of the contract at all times during play of that particular hand.

Another object of this invention is to classify and provide as separate entries the amount of contract to be recorded below the line on the score pad, if made, the amount to be recorded above the line as premium or bonus scores, the amount to be recorded above the line as slam bonus score and the amount in contrasting colors to be recorded above the line in favor of the opponents for penalty scores.

Another object of this invention is a mechanical means

2

of computing the correct and complete score, thereby eliminating miscalculations as well as mistranslation of the somewhat complex printed scoring data.

Yet another object of this invention is the provision of a compensative computer having a plurality of superimposed discs which are relatively rotatable for mechanically solving problems from certain programming information.

A still further object of this invention is the provision of a compensative computer which may be made of an inexpensive material without excessive costs, is small and compact and may be easily carried about or hand held and which may be adapted to be mounted to score pads or suitable stands.

Other objects, advantages and capabilities of the invention will become apparent from the following description, taken in conjunction with the accompanying drawings showing only a preferred embodiment of the invention.

In the drawings:

FIGURE 1 is plan view of the face of the compensative computer of the present invention;

FIGURE 2 is a section view taken along lines 2—2 of FIGURE 1;

FIGURE 3 is a section view taken along lines 3—3 of FIGURE 2;

FIGURE 4 is a section view similar to FIGURE 3 but taken along lines 4—4 of FIGURE 2;

FIGURE 5 is a section view taken along lines 5—5 of FIGURE 2;

FIGURE 6 is a partial section view taken along lines 6—6 of FIGURE 1;

FIGURE 7 is an exploded perspective view of the compensative computer; and

FIGURE 8 is a partial section view taken along lines 8—8 of FIGURE 7.

Referring to the drawings wherein like reference characters designate corresponding parts throughout the several figures, the compensative computer of the present invention is designated generally by the reference character 10. The computer 10 comprises in part a front cover plate 11 and a rear cover plate 12. The rear cover plate 12 has a circular configuration and is generally flat except for the peripheral portion 13 which projects perpendicularly to the main body of the plate and embodies a lip 14 which projects from the peripheral portion upwardly and outwardly to form a partial dove-tail member. At opposite points about the periphery of the peripheral portion 13 there are found relieved portions 15 and 16, each having a longitudinal depressed area 17 and 18 respectively. Integral with the main body portion of the rear cover plate 12 and spaced inwardly in a concentric manner from the peripheral portion 13 is a fixed internal gear 19 of suitable configuration. The center of the rear cover plate 12 has an annular ring 21 projecting outwardly therefrom which embodies a pair of inwardly projecting stop members 22 and 23 the purpose of which will be later described. With the annular ring 21, but integral with the main body of the rear cover plate are two series of detent recesses 24 and 25 with each series being composed of five individual recesses. As seen from FIGURE 3 the stop members 22 and 23 form a division between the series of detent recesses 24 and 25 and set the two series apart from one another.

The front cover plate 11 is adapted to interfit with the rear cover plate 12 to form therebetween an annular chamber 26 in which the movable portions of the present invention are located. The front cover plate 11 generally comprises a perpendicularly extending annular peripheral portion 27 which is so formed as to mate with the peripheral portion 13 of the rear cover plate. Peripheral portion 27 has extending therefrom a lip 28

which projects slightly inwardly forming a partial dovetail that mates with the lip 14 of the rear cover plate. The front and rear cover plates are joined to one another merely by positioning them in registry and then applying pressure to each toward one another so that the lips 14 and 28 have a snap action movement and come to rest as shown by FIGURE 6. The face of the front cover plate 11 has a series of apertures therein by which certain inputs and outputs of the invention may be either set into the computer or extracted therefrom. The first of these apertures is a central circular one, noted by numeral 29, which has a raised periphery 31 upon which there is certain indicia to aid in the computation of score in contract bridge for which the embodiment shown herein is designed. Other apertures of the front cover plate include a vulnerability dial selector window 32, a doubling dial selector window 33, an above the line score window 34 and a below the line score window 35.

As seen by FIGURE 1 the aforementioned apertures of the front cover plate 11 have certain indicia printed nearby to assist the computer operator in using the computer for purposes for which it was designed. These purposes will later be described. However, it should be noted that since the particular embodiment shown herein was designed for use as a bridge score computer the indicia printed on the front cover plate necessarily involve a pre-supposed knowledge of the game of contract bridge and the arrangement of the indicia will be evident to one having that knowledge. The front cover plate 11 shows at the top peripheral surface the numerals 1 through 7 and the notation "AMT. BID" which stands for amount bid and the number of tricks contracted for by the highest bidder. At the lower peripheral surface of the front cover plate the numerals 3 through 13 appear with the notation "TRICKS TAKEN." This indicates the actual number of tricks taken by the player who won the bid and is a number which affects the final score showing throughout the various apertures of the cover plate. The vulnerability dial selector window 32 shows the notation "NON-VUL" and "VULBLE" which notations stand for non-vulnerable and vulnerable. Spaced about the doubling the dial selector window 33 are the indicia "RE-DBLD," "DBLD" and "UN-DBLD" which indicia refer to the bid being redoubled, doubled or un-doubled respectively. On the raised periphery 31 of the center aperture 29 the indicia representing clubs, diamonds, hearts, spades and no trumps are equally spaced about the upper portion of the periphery. Such indicia is used to denote the suit in which the winning bidder is playing the hand.

Located within the annular chamber 26 and adjacent the rear cover plate 12 is a central sun gear 36 having suitable gear teeth 37 about its periphery. The sun gear 36 has a central aperture 38 which is positioned about the annular ring 21 of the rear cover plate so as to centrally locate the sun gear with respect to the rear cover plate.

Concentrically located with respect to the sun gear 36 are a pair of identical selector intermediate gear rings 39 and 41. Gear ring 39 is the "amount bid selector ring" and has mounted extending outwardly from its periphery a bid selector indicator arm 42 which terminates in an indicator knob 43. Indicator arm 42 has at opposite sides detent buttons 42a, 42b wherein button 42b follows depressed area 17 and button 42a is adapted to fit within selected detent recesses 20a to maintain the knob 43 in its desired position. Upon the ring 39 projecting toward the rear cover plate are three gear axles 44 located symmetrically with respect to the center of the gear ring. Upon these gear axles are mounted for rotation suitable planetary gears 45. The planetary gears 45 are adapted to interfit with the internal gear ring 19 of the rear cover plate and rotate thereon at such time as movement is imparted to the gear ring 39. Additionally the planetary gears 45 also engage gear teeth 37 of the central sun gear 36. Therefore, it can be seen

that as movement is imparted to ring 39 and since the rear cover plate 12 is normally stationary, movement will thereby be imparted to the freely rotatable sun gear in a manner relative to the rotation of ring 39.

5 Gear ring 41 is located adjacent ring 39 and is used to indicate upon the front cover plate 11 the number of tricks taken by the player. This is accomplished by the outwardly projecting ring arm 46 and indicator knob 47. Indicator arm 46 has at opposite sides detent buttons 46a and 46b wherein button 46b follows depressed area 18 and button 46a is adapted to fit within selected detent recesses 20b to maintain knob 47 in its desired position. In a manner similar to ring 39, gear ring 41 has projecting in symmetrical fashion from its flat surface three gear axles 48. Upon these axles are mounted planetary gears 49 which, in the present embodiment, are duplicates of planetary gears 45. The gears 49 are adapted to mesh with teeth 37 of sun gear 36 and also to mesh with the internal gear 51 of the circular "above the line" score dial 52. Therefore, as ring 41 is rotated to indicate the number of tricks taken it follows that the score dial 52 will be caused to rotate about twice the distance as the movement of ring 41, and the sun gear 36 will remain stationary.

20 25 The score dial 52 is generally circular in shape and has projecting perpendicularly thereto a peripheral portion 53 which has integral therewith on its interior surface an internal gear 51. The central aperture 54 of score dial 52 is overly large for a purpose later to be described.

30 35 In addition, the dial 52 has about its central aperture a raised annular rim 55 which acts as a bearing surface for other portions of the invention. Printed upon the face of dial 52 are suitable indicia, some of which are of contrasting colors to represent various scores that may be obtained in the game for which this computer is designed. It should be noted at this time that the combination of the rear cover plate 12 with its internal gear 19, central sun gear 36 and the gear ring 39 with the assembled planetary gears combine to form a hypocyclic gear system. In addition the sun gear 36, gear ring 41 with the assembled planetary gears and the score dial 52 with its internal gear 51 combine to form an epicyclic gear system.

40 45 Immediately adjacent the score dial 52 is a "below the line" contract score dial 56 which has a central aperture 57 from the periphery of which extends rearwardly a projecting portion 58 having three symmetrical rearwardly projecting pins 59. When dial 56 is in operative position the pins 59 project rearwardly through the overly large aperture 54 of dial 52 and rest in receiving holes 61 in the forward face of sun gear 36. This obviously locks contract score dial 56 to the movement of sun gear 36 and does not allow independent relative movement. A portion of the contract score dial 56 has a deeply relieved peripheral portion 62 which allows portions of the premium and penalty score dial 52 to be read through aperture 34 of the front cover. A window 62a in the contract score dial 56 allows the scores for a small slam and a grand slam to be read through the front cover plate at the appropriate time.

50 55 60 Immediately forward of, and lying adjacent to, the contract score dial 56 is a generally circular suit selector dial 63. This dial has a relieved peripheral zone 64 much for the same purpose as zone 62 has for dial 56. Inwardly toward the center from the relieved peripheral zone 64 is an elongated aperture 65 providing a window so that the score dial 52 may be read at the appropriate time. A blocking bar 66 separates the relieved peripheral portion 64 and the aperture 65 so that certain selected scores on dial 52 may be blocked out at certain times. The main function of dial 63 is performed by the five separate apertures 67a, 67b, 67c, 67d, 67e which are positioned suitably with the "below the line" score window 35 to present through that window the desired score

corresponding to whatever suit the hand is being played in.

Adjacent the suit selector dial 63 is the circular doubling dial 68 having three lower windows 69, 71 and 72 which are spaced radially from the center at varying distances and also spaced from one another circumferentially. As is apparent this arrangement of windows 69, 71 and 72 divide the "below the line" score window 35 into three parts to reveal only the applicable score. In the upper portion of the doubling dial 68 are three windows 73, 74, and 75 which reveals certain applicable scores from score dial 52. Projecting outwardly through window 33 of front cover plate 11 is the doubling selector button 76 which is adapted to be moved in one of three positions shown by the face of the cover plate in order to move the various windows of dial 68 into position to show the correct score. The doubling selector button 76 has shoulders 76a which allow the button to be placed in the recessed station stops 33a and 33b and 33c which prevent accidental movement of button 76 from a desired station.

The vulnerability dial 77 is generally circular in shape and has a relieved peripheral zone 78 used for both blocking scores and for showing scores from the various scoring dials. Another function of the relieved peripheral zone 78 is to allow free movement of the doubling dial selector button 76. The lower portion of the dial 77 has an aperture 79 to allow scores to be projected through window 35 of cover plate 11. The windows 81, 82, 83, and 84 and 85 allow certain selected scores to be shown through the premium and penalty score window 34. Near the periphery of dial 77, opposite the relieved zone 78, is a vulnerability selector button 86 which projects through the vulnerability selector window 32 of front cover plate and may be positioned in either of the two positions indicated on the cover plate. Positioning of this button obviously presents through the two score windows the applicable score relating to the vulnerability of the person playing the hand. The vulnerability selector button 86 has shoulders 86a which allow the button to be placed in the recessed station stops 32a, 32b which prevent accidental movement of button 86 from a desired station.

To indicate the suit in which the hand is being played a suit indicator knob 91 having a pointing means 92 is located in the center aperture 29 of the cover plate and is used for designating the suit in which the bid was made. The rearmost portion of the knob 91 has an upper detent 93 and a lower detent 94 which are adapted to be received within the respective separate series of detent recesses 24 and 25. The cooperation of the detent and the detent recesses maintain the selector knob 91 in the desired location and prevents it from being inadvertently moved. Along the shaft 91 are a pair of key ways 95 which interfit with the keys 96 which project inwardly into the central aperture 97 of the suit selector dial 63. This construction affixes the dial 63 to the selector knob 91 thereby forcing the suit selector dial to rotate responsive to the knob and so position the suit windows 67a, 67b, 67c, 67d, 67e in front of window 35 so as to present the appropriate score.

In operation of the present invention it should be noted that when the bid selector indicator arm 42 is rotated in a clockwise manner the contract score dial 56 also moves in a clockwise direction by the action of the central sun gear 36 moving responsive to the rotation of the gear ring 39. Because of the differences in gear ratios the sun gear 36 moves about twice the distance the indicator arm 42 moves. Since the sun gear 36 is turning clockwise and the "tricks taken" selector ring 41 is stationary, the resulting movement of the sun gear is transferred through the planetary gears 49 of the epicyclic gear train causing the internal gear 51 of the premium and penalty score dial 52 to turn in a counterclockwise direction.

This counterclockwise motion of score dial 52 positions the dial in proper relation to the amount bid so that the subsequent movement of the "tricks taken" arm 46 will reveal the applicable score through the "above the line" score window 34. When the number of tricks taken is designated by moving the "tricks taken" selector arm 46 in a clockwise direction, the penalty score shown through window 34 will be reduced until the contract is satisfied and further advancement of arm 46 and gear ring 41 will move dial 52 to show a premium score earned. Moving arm 46, which designates the number of tricks taken, actuates only the premium and penalty dial 52 because the sun gear 36 remains stationary in this operation. The contract score dial 56 is actuated only when the bid selector arm 42 and gear ring 39 are moved. However, the movement of gear ring 39 also moves premium and penalty score dial 52 in a manner which is contrary to the direction of movement to the contract score dial 56.

If, in playing the game of contract bridge, the number of tricks taken do not satisfy the contract as indicated by the position of indicator knob 43 then the score showing through window 34 of cover plate 11 will be in red numerals indicating that this is a penalty score. However, when the number of tricks taken satisfies the bid or is greater than the bidded contract the score showing through window 34 will be in black numerals indicating a premium score.

In the configuration shown by FIGURE 1 the computer is set up to show that a bid of 4 was made as is indicated by selector knob 43. The pointing means 92 indicates that the trump suit is hearts and on the left side of the cover plate the vulnerability selector button 86 shows that the bidding player is not vulnerable at the present time. On the right side of the cover plate the doubling selector button 76 indicates that the bid was doubled by the opposing players. Assuming that the hand has been completely played, the tricks taken indicating knob 47 shows that only 8 tricks were taken which means that the bidding player failed on his contract by a total of 2 tricks. This failure shows in window 34 as a penalty score of 300 which would show on the opposing players' score card as an "above the line" score of 300. In window 35 a score of 240 is shown which represents the amount of a contract of four hearts doubled.

Window 34 is designed to show 8 distinct and various scores positioned radially from one another with respect to the center of the computer. In descending order from the outermost score inwardly, the scores indicated would be (a) redoubled scores, (b) doubled scores, (c) scores from bids made in major suits and the no trump suit, (d) scores made from bids in minor suits, (e) a grand slam score bid and made when vulnerable, (f) a grand slam score bid and made when not vulnerable, (g) a small slam bid and made when vulnerable, and (h) a small slam bid and made when not vulnerable. The vulnerability dial 77 divides the upper 4 scoring sections of window 34 into two vertical sections by means of windows 81 and 82 revealing only the right half of window 34 if the player is not vulnerable and only the left half if the player is vulnerable. The vulnerability selector dial 77 also divides the lower 4 scoring sections of window 34 so as to reveal only the scoring sections closest to the center of the computer and the one that is third from the bottom is the side that is not vulnerable and to reveal only the second and fourth section from the bottom if vulnerable. The lower window 35 is divided into 3 radial scoring sections determined by windows 69, 71 and 72 of the doubling dial 68 to reveal only the score that is applicable. The radial scoring section, of lower window 35, that is nearest the center of the computer reveals only the undoubled score, the middle section reveals the doubled score and the outer section shows re-doubled scores. The lower window 35 is also divided into three circumferential scoring sections by suit selector dial 63 and windows

67a, 67b, 67c, 67d, and 67e. By proper use of the present invention it can be seen that there are eight possible scoring sections for premium or penalty scores in the upper scoring half of window 34 and four possible scoring sections of slam scores in the lower half of the window. In the lower window there are nine possible scoring sections for contract scores. When all settings are made on the computer only one score will be revealed in the upper half scoring sections of window 34 and only one score will be revealed in window 35. If either a grand slam or small slam was bid and made the score will be revealed as a separate item in the lower scoring sections of window 34.

The present invention has shown a new and novel compensative computer which may be used for a variety of purposes although it was shown and described herein as a contract bridge score computer. It should also be noted that the computer may be constructed of various materials and it is anticipated that a high impact plastic would be quite suitable to achieve an accurate and low cost item.

While I have particularly shown and described one particular embodiment of the invention, it is distinctly understood that the invention is not limited thereto but that modifications may be made within the scope of the invention and such variations as are covered by the scope of the appended claims.

What is claimed is:

1. A compensative computer comprising, a rear cover plate, a front cover plate having a plurality of apertures therein, the front and rear cover plates adapted to be interfitted to define an enclosed chamber therebetween, a sun gear mounted adjacent the rear cover plate, first and second flat rings positioned concentrically about the periphery of the sun gear, axle means projecting perpendicularly outward from the first and second gear rings, planetary gears mounted for rotation on the axle means, a circular internal gear adjacent the periphery of the rear cover plate, the planetary gears of the first gear ring interfitting with both the sun gear and the internal gear of the rear cover plate, a first indicia bearing disc positioned in overlying relation adjacent the second gear ring, an internally facing gear mounted integrally on the first indicia bearing disc, the planetary gears of the second gear ring interfitting with the sun gear and the gear of the first indicia bearing disc, a second indicia bearing disc positioned adjacent the first indicia bearing disc and fixedly interconnected with the sun gear, a plurality of discs having multiple apertures positioned adjacent the second indicia bearing disc, means controlling the last mentioned discs to selectively present predetermined indicia from the first and second indicia bearing discs for viewing through certain of the apertures of the front cover plate.

2. A compensative computer, the combination recited in claim 1 wherein the front cover plate has a first and second score viewing window and a pair of oppositely located elongated apertures through which variable information may be programmed.

3. A compensative computer, the combination recited in claim 1 wherein indicia is located around the peripheral edge of the front cover plate.

4. A compensative computer, the combination recited in claim 3 wherein, the first and second flat rings each have an arm projecting exteriorly of the chamber whereby the arms may be moved into alignment with the peripheral edge indicia of the front cover plate whereupon such movement repositions at least one of the indicia bearing discs.

5. A compensative computer, the combination recited in claim 1 wherein the plurality of discs positioned adjacent the second indicia bearing disc include a circular

disc having a deeply relieved peripheral portion, a central aperture in the last mentioned disc having inwardly projecting tabs.

6. A compensative computer, the combination recited in claim 5 wherein, a rotatable indicator knob associated with the central portion of the front cover plate and extending rearwardly therefrom, the inwardly projecting tabs positioned within receiving key ways of the indicator knob to allow positive rotation of the last mentioned disc with the knob.

7. A compensative computer, the combination recited in claim 2 wherein, the plurality of discs further including a pair of generally circular discs each having a projecting selector button adapted to pass through one of the elongated apertures of the front cover plate for positioning the pair of discs from exteriorly of the chamber.

8. A compensative computer comprising, a rear cover plate, a front cover plate having a plurality of apertures therein, the front and rear cover plates adapted to be interfitted to define an enclosed chamber therebetween, a planetary gearing system in the chamber adjacent the rear cover plate, a first indicia bearing disc positioned in overlying relation adjacent the planetary gear system, an internally facing gear mounted integrally on the first indicia bearing disc and interfitted with the planetary gearing system, a second indicia bearing disc positioned adjacent the first indicia bearing disc and fixedly interconnected with a portion of the planetary gearing system, a plurality of discs having multiple apertures positioned adjacent the second indicia bearing disc, means controlling the last mentioned discs to selectively present predetermined indicia from the first and second indicia bearing discs for viewing through certain of the apertures of the front cover plate.

9. A compensative computer for use in the game of contract bridge comprising, a rear cover plate, a front cover plate having a plurality of apertures therein, the front and rear cover plates adapted to be interfitted to define an enclosed chamber therebetween, a sun gear mounted adjacent the rear cover plate, first and second flat rings positioned concentrically about the periphery of the sun gear, means located exteriorly of the chamber for positioning the flat rings, axle means projecting perpendicularly outward from the first and second gear rings, planetary gears mounted for rotation on the axle means, a circular internal gear adjacent the periphery of the rear cover plate, the planetary gears of the first gear ring interfitting with both the sun gear and the internal gear of the rear cover plate, a first indicia bearing disc for showing premium and penalty scores positioned in overlying relation adjacent the second gear ring, an internally facing gear mounted integrally on the first indicia bearing disc, the planetary gears of the second gear ring interfitting with the sun gear and the gear of the first indicia bearing disc, a second indicia bearing disc for showing contract scores positioned adjacent the first indicia bearing disc and fixedly interconnected with the sun gear, a plurality of discs having multiple apertures positioned adjacent the second indicia bearing disc, means controlling the last mentioned discs to selectively present predetermined indicia from the first and second indicia bearing discs for viewing through certain of the apertures of the front cover plate, the plurality of discs including a disc showing whether the bidder is vulnerable or not, a disc showing whether the bidder was doubled, re-doubled or not doubled, and means for indicating on the front cover plate the trump suit.
